UNITED STATES PATENT OFFICE.

FRED G. CHAMBERLIN, OF MINNEAPOLIS, MINNESOTA.

DANGER-SIGNAL DEVICE FOR RAILWAYS.

SPECIFICATION forming part of Letters Patent No. 709,469, dated September 23, 1902.

Application filed December 7, 1901. Serial No. 85,020. (No model.)

To all whom it may concern:

Be it known that I, FRED G. CHAMBERLIN, a citizen of the United States, residing at Minneapolis, in the county of Hennepin and State of Minnesota, have invented certain new and useful Improvements in Danger-Signal Devices for Railways; and I do hereby declare the following to be a full, clear, and exact description of the invention, such as will enable others skilled in the art to which it appertains to make and use the same.

My invention has for its object to provide an improved signal or alarm device for indicating to an engineer or other person on a train that they are approaching danger ahead occasioned by a washout of the track or an obstruction upon the track.

To the above ends the invention consists of the novel devices and combinations of devices hereinafter described, and defined in the claims.

The invention is illustrated in the accompanying drawings, wherein like characters indicate like parts throughout the several views.

Figure 1 is a plan view with some parts broken away, showing a portion of a track and illustrating my improved alarm or signal device applied in operative position in connection therewith. Fig. 2 is a transverse vertical section on the line $x^2 x^3$ of Fig. 1; and Fig. 3 is a view corresponding to Fig. 2, but illustrating different positions of the parts.

The numeral 1 indicates the ties, and the numeral 2 one of the rails, of an ordinary railway-track. One of the ties is shown as extended at one end farther than the other ties, and to this projecting end two standards 3 and 4 are shown as secured. To the upper end of the standard 3 is pivotally secured, by a bolt 5 or other device, a sheave 6, having projecting flanges 7. To one of the flanges 7 is secured a disk-like head 8 and to the other is secured an annular frame or holder 9, provided at its center with a bull's-eye or glass disk 10. The head 8 is heavier than the frame 9 and bull's-eye 10, and consequently tends to hold the said parts in the normal position. (Indicated in Fig. 2.)

To the upper end of the standard 4 is applied a signal-lamp 11 of ordinary or any suitable construction. The exposed bull's-eyes 12 of this lamp would usually be of white

glass, while the bull's-eye 10 within the frame 9 would be of red glass. When the parts stand as indicated in Figs. 1 and 3, the red bull's-eye (the numeral 10) will be thrown in front of one of the white bull's-eyes of the lamp 11, and thus the said lamp is made to throw a red light, which will indicate to an engineer or fireman on a train approaching from that side that there is danger ahead.

To small brackets 13 or other suitable support shown as projecting from the end of the long tie is mounted a rock-shaft 24. The rock-shaft 24 carries three arms 14, 14^a, and 25. The arm 14 is connected to the sheave 6 by a chain or other flexible connection 15. This same arm 14 is connected by a chain or flexible connection 16 to one arm of a bell-crank 17, which, as shown, is pivoted to the long tie between the rails. As is shown, this chain 16 runs under a guide-sheave 18 and under one of the rails, the said rail being slightly spaced from said tie by shimming-blocks 19. The other arm of the bell-crank 17 is connected to one end of a wire or other long trip connection 20. This connection 20 may be of any desired length and should extend over that section of the track where washouts are likely to occur or where obstructions, such as heavy rocks or landslides, are liable to roll and slide onto the track. At its extended end the trip connection 20 is anchored to a suitable fixed support, such as a staple 21, shown as driven into one of the ties.

Between certain of the ties which are located between the extremities of the trip connections 20 are placed auxiliary ties 1^a, which are loose, except that they are firmly embedded in the road-bed. The trip connection 20 is passed loosely through staples or similar devices driven into the ties 1 and 1^a. As is evident, if one of the intermediate ties 1 or 1^a should be permitted to lower or to move endwise, as would be the case if a washout should occur, the trip connection 20 would be drawn upon and would force the semaphore afforded by the head 8 and holder 9 from its normal position (indicated in Fig. 2) into the danger-indicating position, (shown in Figs. 1 and 3;) but it would often happen that said trip connection would be broken, or in case of a rolling stone, which might pass over the same, it would be tightened only for

an instant. In either case, with the construction so far described, the semaphore would be operated and then be permitted to drop back into its normal position. To obviate this defect, I provide what I term, broadly, the "semaphore" or "signal" actuator and which is preferably afforded by a coiled spring 23, shown as secured at one end to the side of the long tie and at its other end to the arm 14^a. This spring is so disposed with respect to said arm that when the parts stand in their normal position (indicated in Fig. 2) the line of strain of said spring will be thrown slightly below the pivotal axis of the rock-shaft 24, and hence will assist the weighted head 8 in holding the semaphore in its set normal position. In this normal position (indicated in Fig. 2) the connections 16, 17, and 20 hold the arm 14^a against further downward movement under the tension of the said spring. Now it is evident that a temporary pull on the trip connection 20 will throw the arm 14 far enough to raise the line of strain of said spring above the axis of said rock-shaft 24, so that the said spring then becomes operative to throw the semaphore into the "danger-indicating" position and to there hold the same until the semaphore is again set by hand or otherwise.

To afford an additional signal or alarm, I provide means whereby a torpedo is automatically placed upon the track, where it will be exploded by the wheels of a passing train. This device, in what I consider its best form, is constructed as follows: To a suitable bearing, shown as secured on the long tie, is pivoted the lower end of a torpedo holder or arm 27, to the free end of which an ordinary railroad-torpedo 28 is secured. The arm 27 is connected to the arm 25 by a link 29. When the parts stand in their normal position, the torpedo 28 is held clear of the track and out of the path of the wheels and other parts of a passing train, as indicated in Fig. 2. When the parts are tripped, as already described, and moved into the positions indicated in Figs. 1 and 3, the torpedo is thrown on top of the adjacent rail. The explosion of this torpedo will of course serve to arouse or attract the attention of a sleepy or careless engineer.

It will of course be understood that the construction above described is capable of a large range of modification within the scope of my invention as herein set forth and claimed.

The expression "signal device" or "sig-

nal" is herein used in the broad sense to include either a semaphore or a percussion device. The expression "track" is also used in a broad sense to include the rails, ties, or associated devices placed in the road-bed.

It is of course evident that the trip connection 20 instead of being located between the rails might be located outside of the same and at any desired distance therefrom.

What I claim, and desire to secure by Letters Patent of the United States, is as follows:

1. A danger-signal for railways in combination with the bell-crank 14, actuating-spring 23 and trip connections 16, 17 and 20, the latter of which is anchored to the track at its extended end and is passed through intermediate guides on the track, substantially as described.

2. The combination with a lamp 11, of a semaphore provided with the bull's-eye 10 and sheave 6, the bell-crank 14 connected to said sheave 6 by connection 15, the trip connection 16, 17, 20 connected to said bell-crank and to the track, as described, and the actuating-spring 23 connected to and operating upon the said bell-crank 14, substantially as described.

3. The combination with a railway-track, of a torpedo-holder for moving a torpedo into and out of contact with the track, and means for automatically throwing said holder from an inoperative to an operative position, comprising the bell-crank 14, the actuating-spring 23, and the connection 16, 17, 20, which section 20 is anchored at its extended end and is passed through guides on the intermediate ties, substantially as described.

4. The combination with a railway-track involving auxiliary ties or device placed between the ordinary ties, of a signal device and a trip therefor arranged to be actuated by movements of said auxiliary ties, substantially as described.

5. The combination with the rails and ties of a railway, of auxiliary ties loosely embedded between the said ties, and a signal device involving a flexible trip connection anchored at its extended end and passed loose through guides on the said auxiliary ties, substantially as described.

In testimony whereof I affix my signature in presence of two witnesses.

FRED G. CHAMBERLIN.
